UNITED STATES PATENT OFFICE

RAY D. HULSLANDER, OF AKRON, OHIO, ASSIGNOR TO THE FIRESTONE TIRE & RUBBER COMPANY, OF AKRON, OHIO, A CORPORATION OF OHIO

APPARATUS FOR FEEDING POWDERED MATERIAL

Application filed July 31, 1930. Serial No. 472,018.

This invention relates to apparatus for feeding powdered material and more particularly to mechanism for dusting or otherwise treating rubber goods with soapstone, 5 starch or the like.

The general object of the invention resides in the provision of an inexpensive, foolproof, efficient apparatus which is readily adapted to a plurality of powder-feeding uses.

10 It is an object of the invention to provide apparatus which can be controlled to vary the concentration and amount of powder supplied.

The above and other objects of the invention are achieved by the apparatus illustrated in the accompanying drawings and described below, it being understood that the invention is not limited to the exact details thereof shown and described.

20 In the drawings,

Figure 1 is a side elevation of the apparatus embodying the invention;

Figure 2 is a front elevation of the apparatus shown in Figure 1;

25 Figure 3 is a plan view of the apparatus illustrating it in use on a tubing machine;

Figure 4 is a vertical sectional view of the vibrator and nozzle incorporated in the invention; and

30 Figure 5 is a bottom plan view of the nozzle shown in Figure 1 and is taken on line 5-5 of Figure 1.

Referring to the drawings, the numeral 7 indicates a frame which serves to carry a 35 hopper or bin 8 of any appropriate size and shape, the top of which may be open or closed. The hopper 8 is funnel-shaped and at its bottom is formed with an opening 9. An electric vibrator 11 is secured over the 40 bottom of the hopper 8 which is provided with a bottom flange 12 for this purpose. The vibrator 11 is of any standard type and in itself forms no part of the present invention.

45 The usual diaphragm of the vibrator is replaced by a rubber diaphragm 13 which is pierced by a rubber tube 14 which opens adjacent the opening 9 in the hopper. The tube 14 may be vulcanized, cemented or otherwise secured to the diaphragm 13.

In order to control the size of the opening in the tube 14, a needle valve 15 is provided which extends downwardly into the tube 14 as shown in Figure 4. The needle valve 15 is journaled in suitable bushings on the hopper, including a nut bushing 16, and is provided at its upper end with a handwheel 17 for purposes of adjustment.

The tube 14 extends down into a T 18 in one end of which is screwed a nozzle 19 connected through conduit 21 to a supply of compressed air. An air filter 22 and a control valve 23 are provided in the conduit 21.

In the embodiment of the invention shown in Figure 1 the other side of the T 18 is connected by a conduit 24 with a nozzle or distributor head 25 whereby the powdered material can be supplied for any purpose, such as, for example, coating the outside of a green tube 26, carried on a conveyor 27, with the powdered material. A hood may be provided about the conveyor and discharge nozzle as will be understood.

Another adaption of the invention is illustrated in Figure 3 wherein the apparatus 75 is utilized to supply the powdered material to the interior of an extruded or tubed automobile inner tube to prevent the inner surfaces of the walls from sticking together. Referring to Figure 3, an extruder of standard design is indicated at 28, the conduit 24 from the powder-feeding apparatus being connected to the internal mandrel or die as is well understood in the art.

In the operation of the apparatus the hopper or bin 8 is filled with the desired powdered material and the electric vibrator is started which will cause the powder to feed down through the tube 14. The amount of powder passing through the tube can be controlled of course by the position of the needle valve 15.

Air supplied through the conduit 21 and nozzle 19 serves to atomize the powder fed through the tube 14 and forces it out the conduit 24 in an intimate mixture of air and powder. The position of the nozzle 19 and the T 18 is such that it produces a sucking action on the tube 14 which assists in the feeding action of the powder therethrough.

By adjusting the needle valve 15 by way of handwheel 17, and also adjusting air valve 23 the amount of powder supplied as well as the relative amounts of air and powder can be very accurately adjusted and controlled.

As many changes could be made in the construction and in the uses of the invention, it is intended that all matter herein disclosed shall be interpreted as illustrative only and not in a limiting sense. Accordingly, various modifications and applications of the invention can be resorted to without departing from the spirit of the invention or the scope of the appended claims.

15 What is claimed is:

1. Powder-feeding mechanism comprising a hopper for containing the powder, a vibrator secured to the bottom of the hopper, a flexible rubber diaphragm in said vibrator, 20 a tube piercing said diaphragm and secured thereto, said tube being in alignment with an opening in the bottom of the hopper, and a needle valve adjustably controlling the opening in the tube.
2. Powder-feeding mechanism comprising a hopper for containing the powder, a vibrator secured to the bottom of the hopper, a flexible rubber diaphragm in said vibrator, and a flexible discharge tube piercing 30 said diaphragm and secured thereto, said tube being in alignment with an opening in the bottom of the hopper.
3. Powder-feeding mechanism comprising a hopper for containing the powder, a vibrator secured to the bottom of the hopper, a diaphragm in said vibrator, and a tube piercing said diaphragm and secured thereto, said tube being in alignment with an opening in the bottom of the hopper.
4. Powder-feeding mechanism comprising a hopper for containing the powder, a vibrator secured to the bottom of the hopper, a diaphragm in said vibrator, a discharge outlet connected to said diaphragm, and a 40 needle valve adjacent said outlet for defining an adjustable orifice in said diaphragm.
5. In combination, a hopper having a funnel-like discharge opening, a diaphragm closing said opening, a discharge tube piercing said diaphragm, means for controlling the size of the passage through said discharge tube, and means for vibrating said diaphragm.
6. In combination, a hopper having a funnel-like discharge opening, a diaphragm closing said opening, a discharge tube piercing said diaphragm, and means for vibrating said diaphragm.
7. In combination, a hopper having a funnel-like discharge opening, a diaphragm closing said opening, a discharge tube piercing said diaphragm, a valve for controlling the size of the passage through said discharge tube, and means for vibrating said diaphragm adjacent said valve.

8. In combination, a hopper having a funnel-like discharge opening, a diaphragm closing said opening, a discharge tube piercing said diaphragm, means for controlling the size of the passage through said discharge tube, means for vibrating said diaphragm, and means for maintaining the discharge end of said discharge tube at sub-atmospheric pressure.

9. Powder-feeding mechanism comprising a hopper, a passage extending from said hopper, said passage including a relatively fixed and a relatively movable portion defining a discharge orifice, and means for vibrating said relatively movable portion for feeding powder from said hopper.

In witness whereof I have hereunto affixed my signature this 28th day of July, 1930.

RAY D. HULSLANDER.
